U.S. Appl. No. 29/383694, Applicants William L. Driskell et al., filed Jan. 18, 2011.

Primary Examiner — Catherine Tuttle

CLAIM

The ornamental design for a dispensing system, as shown and described.

DESCRIPTION

FIG. 1 is an isometric front, top and left side perspective view of the dispensing system showing our new design;

FIG. 2 is a front elevational view thereof;

FIG. 3 is a rear elevational view thereof;

FIG. 4 is a left side elevational view thereof, the right side elevational view being a mirror image of the left side;

FIG. 5 is a top plan view thereof; and,

FIG. 6 is a bottom plan view thereof.

The broken lines are included for the purpose of illustrating portions of the dispensing system that form no part of the claim. The broken line immediately adjacent the shaded area in FIG. 6 further serves to define the lower boundary of the claim.
